UNITED STATES PATENT OFFICE.

CHARLES F. J. DETERS, OF DAVENPORT, IOWA.

MECHANICAL MOVEMENT.

SPECIFICATION forming part of Letters Patent No. 644,351, dated February 27, 1900.

Application filed October 30, 1899. Serial No. 735,217. (No model.)

To all whom it may concern:

Be it known that I, CHARLES F. J. DETERS, of Davenport, county of Scott, and State of Iowa, have invented a new and useful Improvement in Mechanical Movements; and I do declare that the following specification, taken in connection with the drawings making a part of the same, is a full, clear, and exact description thereof.

10 This invention relates to that class of mechanical movements where a rotary reciprocating motion of one shaft is obtained by continuously revolving another or power shaft placed at right angles thereto in one direction, and is especially useful when used in the operation of a washing-machine, churn, or wherever it is desired to use a rotary agitating movement; and the invention consists of an improved gearing and other mechanism 15 by which the rotary motion of the power-shaft is transformed into said reciprocating rotary motion of the other shaft placed at right angles thereto.

In the accompanying drawings, Figure 1 is 20 a side view of my improved mechanical movement mounted in a suitable frame. Fig. 2 is a front view of the same, showing the movable parts in one position; and Fig. 3 shows the same parts in a different position.

25 A represents the frame, which carries the operating parts.

B is the power-shaft, mounted in bearings in the frame A and adapted to be turned in one direction and to the outer end of which 30 may be secured a fly-wheel or crank for convenience in revolving it.

C is the crank-arm, one end of which is fixed to the inner end of said power-shaft B and having a pin or bolt D fixed to its other 35 end and projecting at right angles therefrom.

The power-shaft B, crank-arm C, and bolt D may, if desired, be cast in a single piece.

Upon the bolt D is loosely secured one end 40 of a connecting-arm E. The other end of said arm is loosely connected to one end or corner 45 of a segmental casting F, which segmental casting is provided with a core through its center and adapted to be mounted upon and to turn upon a short shaft or spindle G, projecting from and preferably a part of the frame A. This segmental casting is provided

with beveled teeth or cogs on one of its sides and close to its periphery. These teeth are adapted to engage the teeth or cogs of a beveled gear wheel or pinion H, secured to a 55 shaft or rod I, which shaft is mounted in bearings in the frame A, so as to revolve in said bearings.

To insure the engagement of the teeth of the segmental casting with those of the pinion and to prevent strain upon said casting, a lug J, projecting upwardly from the base of the frame A, may be provided.

This mechanism is adapted to be operated in the following manner: When the parts are 60 in the position shown in Figs. 1 and 2 and the shaft B is revolved toward the right, the arm E will exert a downward pressure against the segmental casting to which it is connected, and said segmental casting being mounted on 65 the short shaft G will turn thereon, and the teeth on said casting F engaging the teeth on the pinion will of course turn said pinion and the shaft I, to which it is secured. When the segmental casting reaches the position shown 70 in Fig. 3, the pressure of the arm E against it is released; but if the turning of the shaft B is continued the arm E will naturally be drawn upward and after moving but a short distance will begin to pull the end of the segmental casting to which its one end is secured 75 upward with it, and the engagement of the teeth with those of the pinion will of course cause said pinion and shaft I to be reversed. Thus in one complete revolution of the power- 80 shaft B the shaft I is revolved first in one direction and then reversed and revolved in the opposite direction the same distance, the rotary reciprocating motion of said shaft I being thus obtained in a simple and efficient 85 manner.

Having thus described my invention, I claim as new and desire to secure by Letters Patent—

1. In a mechanical movement a crank-shaft 90 suitably mounted to revolve in a frame, a segmental casting loosely mounted upon a shaft and provided with cogs upon one of its sides; an arm connecting said crank-shaft and segmental casting; a pinion upon a revolving 95 shaft, the teeth of said pinion adapted to engage the teeth of said segmental casting for

the purpose of imparting a reciprocating rotary motion to said pinion and the shaft to which it is secured.

2. A crank-shaft mounted to revolve in a suitable frame, a segmental casting provided with teeth or cogs on one of its sides and mounted to revolve upon a shaft or spindle; an arm loosely connecting said segmental casting with said crank-shaft.
3. In a mechanical movement a crank-shaft mounted to revolve in bearings in a suitable frame, the segmental casting F provided with teeth on one of its sides and loosely mounted

upon a shaft projecting from the frame; an arm E loosely connecting said crank-shaft and segmental casting; a pinion H secured to a shaft mounted to revolve in bearings in the frame, the teeth of said pinion engaging the teeth on the segmental frame and a lug J substantially as and for the purposes herein described.

CHARLES F. J. DETERS.

In presence of—

T. A. MURPHY,
J. C. ANDERSON.
